UNITED STATES PATENT OFFICE.

JOHN W. GOODERHAM, OF YONKERS, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed July 20, 1923, Serial No. 652,678.

This invention relates to telephone systems and more particularly to means in such systems for controlling indicating devices by current impulses of various characteristics.

It is an object of the present invention to provide an improved organization of circuits and apparatus for determining the characteristics of such impulses.

10 This invention constitutes an improvement over U. S. Patent No. 1,438,743 granted to Edgar H. Clark, December 12, 1922 which relates to a telephone system in which means are provided by which an operator may be informed visually of the number of a wanted subscriber. The means for so doing includes registers which may be set in accordance with the called number, an impulse transmitting switch and an organization of relays and indicators at the operator's position.

Owing to the irregularities introduced in the commercial manufacture and adjustment of parts which go to make up the impulse transmitting switch, it is possible in practice that brief false impulses may occur between the pulses intended to be sent, which pulses may be sufficient to cause the incorrect operation of the indicators. These false impulses can, of course, be eliminated by perfectly adjusting each switch, but in a telephone system employing hundreds of these switches, such a procedure would be decidedly uneconomical.

35 Accordingly, a feature of the present invention is the elimination of such false impulses by the use of a novel arrangement of the impulse controlling and transmitting means.

40 A further feature of the present invention lies in the provision of individual circuits for the transmission of impulses of different characteristics as far as the trunk circuit. Impulses of all characteristics are then transmitted over said trunk circuit.

45 This and other features of the invention will appear in the accompanying drawing and description together with the appended claims.

50 The drawings with Fig. 2 placed below Fig. 1 and with Fig. 3 placed at the right of Fig. 2 diagrammatically represent a portion of a telephone system employing the present invention. Fig. 1 shows a calling subscrib-

er's substation and line with brushes of a 55 district selector at an operator's position, a calling plug and jack at a second operator's position and a called subscriber's substation apparatus and line. Within the small dotted rectangle at the left hand side of Fig. 1, 60 there are shown the brushes of a cord finder switch which operates to connect an idle sending device to the cord circuit which has been connected to the calling line. Within the large dotted rectangle at the right hand side 65 of Fig. 1, there are shown an operator's key set and the registers of the sending device for controlling the transmission of impulses to the number indicating device. Within the larger dotted enclosure at the left of Fig. 1, 70 there is shown an impulse transmitting device which, under the control of the registers, transmits various combinations of impulses to actuate the number indicating device. 75

In Fig. 2, there are shown the various relays which control the lighting of the proper stations lamp as well as the switching relays which operate to control the actuation of the thousands, hundreds, tens and units indicating devices in proper sequence. 80

Fig. 3 in its lower right hand corner shows the lamps and controlling relays for indicating the thousands digit; at the lower left hand corner, the hundreds; at the upper left hand corner, the tens; and at the upper right hand corner, the units lamps and the relays for controlling them. 85

In this disclosure, the showing of the apparatus and circuits for selecting the second 90 or B operator's position has been abbreviated but it may be of the character of the system disclosed in patent to Lundell No. 1,168,319, January 18, 1916 or it may be similar to the system shown in the patent to E. 95 H. Clark No. 1,334,735 of March 23, 1920.

The trunk selecting switch referred to in the description may be of the type illustrated in the patent to Craft and Reynolds 1,123,696 of January 5, 1915, although it will 100 be readily understood that any automatic selector switch can be employed in this system, without departing from the spirit of the invention.

In the description, reference is made to 105 sequence switches and registers, the structure of which may be similar to that shown in the patent to Reynolds and Baldwin 1,127,808

of February 9, 1915. It is to be noted, however, that a revolution of the impulse sequence switch is divided into twenty positions of eighteen degrees each instead of the usual arrangement of eighteen positions of twenty degrees each. This is merely a matter of convenience and introduces no change in the operation of the switch.

It is also to be noted that this invention is equally applicable to systems such as that disclosed in U. S. Patent 1,395,977 granted to F. A. Stearn and F. J. Scudder, November 1, 1921, that is, to systems in which the registers take the form of step-by-step switches or are set under the control of the subscriber without the intervention of an operator.

In general, the system of the present disclosure comprises a set of operator's keys which controls sequence switch registers, all of which are shown in the dotted rectangles at the right of Fig. 1; a switching device for sending impulses as determined by the sequence switch registers as shown in the larger left hand dotted enclosure in Fig. 1; and an arrangement of relays for receiving impulses as shown in Figs. 2 and 3.

In Fig. 2, there are shown three relays in series 201, 202 and 203 which respond directly to the transmitted impulses. These relays in turn control a combination of two relays 207 and 209 which have a peculiar interaction which has been set forth in the above identified Patent No. 1,438,743 to E. H. Clark. A set of relays such as 206 and 210 is provided for each one of the digits of the called number and these relays are controlled through the interaction of the relays 207 and 209. Obviously, a greater number of digits such as would be required by a call through what is known as a "tandem" office could be cared for by causing the impulse switch to make an additional revolution, additional registers being provided. As the means for doing so forms no part of the present invention, the disclosure has been limited, for simplicity, to a five digit number.

There is provided a set of indicating lamps for each one of the digits of the called number, each set of lamps being controlled by a set of lamp controlling relays as shown in Fig. 3. The set 321, etc., controls the thousands lamps; the set 331 etc., controls the hundreds lamps, the set 341, etc., controls the tens lamps and the set 351, etc., controls the units lamps. As shown in Fig. 2, the set 262, etc., controls the stations lamps.

The impulses transmitted by the sequence switch 114 in Fig. 1 are in the nature of a code, which consists essentially of heavy negative impulses between which may be interposed light positive impulses, the heavy negative impulses being superimposed on light negative impulses which serve as

switching impulses. The positive impulses may be omitted.

The positive impulses are produced by current from grounded battery, flowing through high resistance 142, cams controlled by sequence switch 114, and cam contacts closed by the setting of the registers to brush 105. The light negative impulses are produced by current from grounded battery, through high resistance 143, to brush 106, while the heavy negative impulses are produced by current from grounded battery, through resistance 143 and over a parallel path through low resistance 144 and cams controlled by sequence switch 114 and cam contacts closed by the setting of the registers to brush 106. Thus in effect, switching cams 131 to 133 and register cams 151, 153, 156, 158 and 159 together with battery and resistance 142 form a generating device for positive impulses only, while switching cams 145 to 149 and register cams 150, 157, 152, 154 and 155 together with battery and resistance 144 form a generating device for negative impulses only.

Attention is directed to the fact that the paths followed by the positive impulses from battery to brush 105 are entirely separate from those followed by the negative impulses from battery to brush 106. In no case, does the same cam serve for both negative and positive impulses. While battery through high resistance 143 is continuously connected to the side of the line leading to brush 106, it produces no effect at the time of sending positive pulses, being shunted out by ground on cam 140.

In the disclosure of the above mentioned Patent No. 1,438,743 to E. H. Clark, it may be seen that only two sequence switch cams are used for transmitting all the heavy pulses for each digit, one on the register sequence switch and one on the impulse sequence switch. Therefore, if the cams on the impulse sequence switch, which feed the successive pulses that go to make up the code for a given digit, are not properly adjusted, but overlap a little, it is possible for heavy current intended for the preceding or succeeding impulses to find a momentary path over the line in the opposite direction, thus causing a momentary heavy pulse where one may not have been intended. The separation of the leads from battery, through the impulse switch and the registers to the opposite sides of the line, in accordance with the present invention, entirely eliminates the possibility of the current for the negative impulses finding a path over the positive cams to the line. Cam overlap may prolong a pulse but it cannot feed it out to the wrong side of the line. It is also to be noted that the positive cams of the impulse switch are closed from slightly before the time of the first positive pulse of a digit to slightly after the time for the second

positive pulse of a digit, thus preventing any surge of current which may occur due to the closure of the battery lead from interfering with an open or non-pulse period.

5 Attention is also called to the fact that the circuit for the pulses are further separated by having the circuits for the first pulse carried through one cutting of the register and impulse switch cams and the second pulse 10 through a second cutting on these cams, thus additionally insuring the individuality of the pulses.

The code of impulses is shown diagrammatically in the upper part of Fig. 2. Positive impulses are represented by a plus sign, 15 light negative impulses by a light minus sign and heavy negative impulses by a heavy minus sign. Where no positive impulse is to be sent, the corresponding section of the 20 table has been left blank. Each train of impulses consists of four divisions, each division assigned alternately to a positive or negative pulse. Where no positive pulse is to be sent, there is a corresponding interval 25 in the train of impulses so that the trains for the various digits follow one another and form one long series of impulses.

As will hereinafter appear, the lamp controlling relays such as 321, 322, 323, and 324 30 are energized whenever an impulse of positive current or an impulse of heavy negative current is transmitted and thus the codes diagrammatically shown give an indication of which lamp controlling relays will be energized, it being noted that the final digit of 35 the numbers applied to the relays in each set is the same as the number at the head of the corresponding column in the code shown in Fig. 2. For instance, in the numerical code, 40 the series of impulses for the digit 6 consists of first, a positive impulse, second, a light negative impulse, third, a blank, and fourth, a heavy negative impulse. As indicated, the first and fourth relays will be energized according to this code. The stations 45 code corresponds to the numerical code except that no initial positive impulses are sent.

The method of establishing a connection from a calling substation as shown at 101 50 to a called substation as shown at 102 will now be described. When the calling subscriber removes his receiver from his switchhook, a signal (not shown) is lighted at an operator's position. This operator, known 55 as an A operator, thereupon connects the cord circuit conductors 103 and 104 to the calling line manually or by any other suitable means. As soon as the A operator has connected the cord circuit to the calling line, 60 a cord finder whose brushes are indicated at 105 and 106 operates to connect an idle sending device with the cord circuit taken for use. When the operator connects the cord circuit to the calling line, she ascertains the 65 number of the wanted subscriber and pro-

ceeds to set up this number on the keyboard of her sending device.

Let us assume that the wanted number is 4568 station W. The operator will then 70 depress the corresponding stations, thousands, hundreds, tens and units keys in response to which the associated sequence switch registers will be moved and the stations register 109 will come to rest in position 7, the thousands register 110 will stop 75 at position 4, the hundreds register 111 in position 5, the tens register 112 in position 6 and the units register 113 in position 8.

It will be assumed that the automatic 80 trunk selecting switch whose brushes are indicated by the numerals 107 and 108 has been set to select the proper trunk for connecting the calling subscriber with the B operator's position at the office in which the 85 wanted line terminates. It will be assumed that the sequence switch associated with this trunk selecting switch has been moved into position 11.

After the sending device has been set, and 90 when the trunk selecting switch has been operated to extend the calling line to the B operator's position at the desired office, the sequence switch associated with the cord 95 finder will be in position 7 where a circuit will be established to energize relay 117. 100 This circuit may be traced from ground, sequence switch cam 116, winding of relay 117, sequence switch cam 118 (position 1) brush 105, upper contact of sequence switch cam 119, brush 108, lower armature and back contact of relay 120, lower left hand winding of repeating coil 121, winding of relay 123 to grounded battery. Relays 117 and 123 are operated by current flowing over 105 this circuit. Relay 117 by the attraction of its armature closes a circuit from ground, armature and front contact of relay 117, winding of relay 115 to grounded battery whereby relay 115 is energized. At the front contact and armature of relay 123, a 110 circuit is closed from ground, back contact and armature of relay 125, lamp 126, to grounded battery. Lamp 126, in lighting, indicates to the manual operator that a call is awaiting attention and also indicates the 115 trunk over which the call has been extended. The manual operator thereupon depresses key 127 to associate the number indicating device with the trunk over which the call has been extended. 120

Upon the depression of key 127, a circuit is closed from ground, winding of relay 120, contact of key 127, conductor 128, winding of relay 200 to grounded battery. Relay 200 125 attracts its armatures, to apply ground to the various controlling leads of the number indicating device. At the same time, relay 120 attracts its armatures and at its lower armature interrupts the energizing circuit of relay 117. With this relay deenergized, 130

a circuit is closed from ground, through its armature and back contact, armature and front contact of slow-to-release relay 115, magnet of sequence switch 114 to grounded 5 battery to move the sequence switch 114 out of position 1 whereupon it will, under the control of its master contact 124, rotate through its various operating positions back to position 1, during which a complete 10 set of impulses is transmitted to the relays 201, 202, and 203. Relay 203 is marginal and responds only to impulses of heavy current, relay 201 responds only to positive impulses, and relay 202 responds only to 15 negative impulses, the armature of these relays being normally retracted.

As has been mentioned, no positive pulses are sent out in the first period of the train for the stations code. Accordingly, the 20 upper contact of cam 139 is not closed during the time that the sequence switch 114 is passing through positions 1+1½ and the corresponding connection to positive cam 150 of stations register 109 is omitted.

25 When sequence switch 114 moves into position 2, a circuit is closed from grounded battery, through high resistance 143, and in parallel through low resistance 144 over the upper contact of cam 145, and lower 30 contact of negative cam 150 of stations register 109 to cord finder brush 106, thence by way of the upper contact of cam 135, trunk selector brush 107, upper armature and front contact of relay 120, conductor 35 204, winding of marginal relay 203, winding of negatively polarized relay 202, winding of positively polarized relay 201, conductor 134, lower armature and front contact of relay 120, trunk selector brush 108, 40 upper contact of cam 119, cord finder brush 105, upper contact of cam 140 to ground. Since the impulse circuit extends through low resistance 144, marginal relay 203 is energized and since this impulse is negative, 45 relay 202 attracts its armature and closes a circuit from grounded battery, left winding of relay 209, winding of relay 207, left armature and back contact of relay 209, armature and front contact of relay 202, 50 conductor 208, outer armature and front contact of relay 200 to ground. The left winding of relay 209 is a holding winding and is able only to hold the armatures of this relay attracted when once they have 55 been actuated by the right or pull-up winding of this relay. Thus, relay 209 does not attract its armatures but relay 207 does attract its armatures in this circuit. At the inner right front contact and armature of 60 this relay, a circuit for the right winding of relay 209 is closed, but this winding is short-circuited at this time as fully explained later.

At the outer right front contact and armature of relay 207, an energizing circuit for

relay 206 is completed from grounded battery, winding of this relay, inner left armature and back contact of relay 210, through the outer right armature of relay 207 to ground over conductor 208. Relay 206 attracts its armatures and at its inner right front contact and armature closes an energizing circuit for relay 210 but this last mentioned relay is short-circuited at this time and does not attract its armatures. Due to the energization of marginal relay 203 together with the energization of relay 202, a circuit is closed for stations relay 262 extending from grounded battery, left winding of relay 262, inner right armature and back contact of relay 210, outer right armature and back contact of relay 209, armature and front contact of relay 203, armature and front contact of relay 202 to grounded conductor 208. Relay 262 energizes and locks through both windings and its right armature to grounded conductor 208.

When sequence switch 114 moves out of position 2½, relay 202 deenergizes and retracts its armature removing the short circuit about the right hand winding of relay 209. Relay 209 operates in a circuit from grounded battery, through the left winding of relay 209, winding of relay 207, right winding of relay 209, inner right front contact and armature of relay 207 to ground over conductor 208.

In positions 4+4½ of sequence switch 114, a heavy negative impulse is transmitted from grounded battery, low resistance 144, lower contact of cam 145, upper contact of negative cam 150 of stations register 109 in parallel with resistance 143, brush 106 and over the circuit previously described through relays 201, 202, and 203, back to brush 105 and to ground over the upper contact of cam 140. In response to this heavy negative impulse, relays 202 and 203 again attract their armatures. With both of these relays energized, stations relay 264 is actuated over a circuit from grounded battery, left winding of relay 264, outer right hand armature and back contact of relay 210, outer right armature and front contact of relay 209, armature and front contact of relay 203, armature and front contact of relay 202, to grounded conductor 208. Relay 264 is energized and at its right front contact and armature completes a locking circuit for itself from grounded battery through both its windings in series to ground over conductor 208.

Relay 202 also completes a holding circuit for relay 209 from grounded battery, left winding of relay 209, left hand armature and front contact of relay 209, armature and front contact of relay 202, to grounded conductor 208. Relay 207 is short-circuited and retracts its armatures. The short circuit

115

120

125

130

about relay 210 is maintained at this time by way of the inner right armature and front contact of relay 209 to grounded conductor 208. As soon as sequence switch 114 leaves 5 position 4½, relay 202 becomes deenergized and the holding circuit for relay 209 is opened. The release of relay 209 removes the shunt around relay 210 and this relay attracts its armatures and locks in series 10 with relay 206 through the inner right armature and front contact of relay 206 to grounded conductor 208. This completes the selection of the stations lamp controlling relays, relays 262 and 264 having been 15 actuated and locked.

Since the thousands register 110 has been set in position 4, when sequence switch 114 is moved through positions 5+5½, no positive pulse will be sent out.

20 When sequence switch 114 moves through positions 6+6½, no path is closed through low resistance 144 to brush 106 and a light negative pulse is sent from grounded battery through high resistance 143 over the above 25 traced circuit and back to ground at the upper contact of cam 140. Relay 202 energizes and again energizes relay 207. Relay 207 attracts its armature to prepare at its inner right front contact and armature an energizing circuit for relay 209, and at its outer front contact and armature completes an energizing circuit for relay 211 from grounded battery, winding of this relay, inner left armature and back contact of relay 213, inner left armature and front contact of relay 210, outer right armature and front contact of relay 207 to ground over conductor 208. When sequence switch 114 moves 30 out of position 6½, relay 202 deenergizes and removes the shunt from the right winding of relay 209. This relay energizes over its two windings and the winding of relay 207 in series.

With sequence switch 114 in positions 45 7+7½, a positive impulse is transmitted from grounded battery, resistance 142, lower contact of cam 132, upper contact of positive cam 151 of thousands register 110 lower, contact of cam 139, over the previously described circuit and back to ground at the lower contact of cam 140. Relay 201 attracts its armature and closes a circuit from grounded battery, left winding of thousands lamp relay 323, conductor 302, outer right 50 armature and back contact of relay 214, outer right armatures and front contacts of relays 211 and 206, left armature and front contact of relay 207, armature and front contact of relay 201 to grounded conductor 208. Relay 323 attracts its armatures and completes a locking circuit for itself from grounded battery, through both windings in series, its right front contact and armature, conductor 301, inner left front contact and armature of relay 200 to ground.

When sequence switch 114 passes through positions 8+8½, a light negative impulse is transmitted from grounded battery, through resistance 143, since the contacts of negative cam 157 are not closed in position 4 of register 110. In response to this weak impulse, relay 202 is energized closing the holding circuit for relay 209 and shunting relay 207. Relay 207 retracts its armatures but the shunt around relay 213 is maintained at the 70 inner right hand armature of relay 209, as in the case of relay 210. When sequence switch 114 leaves position 8½, relay 202 is deenergized, permitting relay 209 to retract its armatures and relay 213 to lock in series 75 with relay 211 and the front contact of relay 211 to grounded conductor 208. This completes the selection of the thousands lamp controlling relays, relay 323 alone having been actuated.

80 Since the hundreds register 111 is set in position 5, no positive pulse will be sent in position 9+9½ of sequence switch 114.

In position 10+10½, a light negative pulse is sent in response to which relay 202 85 is energized. Relay 207 is again energized through the left hand winding of relay 209 and closes a circuit for relay 214 extending from grounded battery, winding of relay 214, inner left armature and back contact of relay 215, inner left armatures and front contacts of relays 213 and 210, outer right armature and front contact of relay 207 to grounded conductor 208. Relay 214 attracts its armatures and at its innermost 90 right hand armature and front contact closes an energizing circuit for relay 215.

With sequence switch 114 in positions 105 11+11½, no positive pulse will be sent out but when sequence switch 114 leaves position 10½, relay 202 releases and relay 209 operates in series with relay 207.

In positions 12+12½ of sequence switch 114, a heavy negative impulse is sent out 110 over a circuit extending from grounded battery, low resistance, 144 lower contact of cam 147, upper contact of negative cam 152 of hundreds register 111 to brush 106 and thence over the impulse circuit to ground at the upper contact of cam 140. In response to this impulse, relays 202 and 203 are energized and complete a circuit from grounded battery, left hand winding of relay 334, conductor 300, outer right armature and back contact of relay 215, outer left armatures and front contacts of relays 213 and 210, outer right armature and front contact of relay 209, armature and front contact of relay 203, armature and front contact of relay 202, to grounded conductor 208. Relay 115 120 334 attracts its armatures and completes a locking circuit for itself over conductor 301 to ground.

Relay 202 also completes the holding circuit for relay 209 and shunts relay 207 which 125 130

relay retracts its armatures. As soon as sequence switch 114 moves out of position 12½, relay 202 retracts its armatures and relay 209 releases, removing the shunt closed 5 at its inner right hand armature and front contact around relay 215, and permitting relay 215 to operate in series with relay 214 through the innermost armature and front contact of relay 214 to grounded conductor 10 208. This completes the selection of the hundreds lamp controlling relays, relay 334 alone having been actuated.

It will now be noted that the tens register 112 is set in position 6. With sequence 15 switch 114 in position 13+13½, a positive impulse is transmitted from grounded battery, through resistance 142, lower contact of cam 133, lower contact of positive cam 153 of tens register 112, upper contact of cam 20 139, over the circuit previously described to ground through the lower contact of cam 140. Relay 201 is actuated and completes an energizing circuit for the tens lamp controlling relay 341 extending from grounded 25 battery, left winding of relay 341, conductor 304, middle right armature and back contact of relay 217, middle armature and front contact of relay 214, left armatures and front contacts of relays 211 and 206, left armature 30 and back contact of relay 207, armature and front contact of relay 201 to grounded conductor 208. Relay 341 attracts its armature and locks to grounded conductor 301.

With sequence switch 114 in positions 35 14+14½, a light negative impulse is transmitted from grounded battery, resistance 143, over the previously described circuit to ground through the upper contact of cam 140. In response to this impulse, relay 202 40 attracts its armature. Relay 207 is energized in the manner previously described and attracts its armatures to complete a circuit for relay 217 from grounded battery, winding of this relay, inner left armature 45 and back contact of relay 218, inner left armatures and front contacts of relays 215, 213 and 210, outer right armature and front contact of relay 207 to grounded conductor 208.

50 With sequence switch 114 in position 15+15½, no positive impulse is sent out but relay 202 is permitted to retract its armature resulting as before in the actuation of relay 209.

55 In position 16+16½ of sequence switch 114, a heavy negative impulse is transmitted from grounded battery, resistance 144, lower contact of cam 148, upper contact of negative cam 154 of tens register 112 over the 60 circuit previously traced and back to ground through the upper contact of cam 140. Relays 202 and 203 are energized. In the manner previously described, relay 207 becomes short-circuited and retracts its armatures. 65 Relay 341 is also energized over a circuit

including grounded battery, left hand winding of relay 344, conductor 306, the outer right armature and back contact of relay 218, the outer left armatures and front contacts of relays 215, 213 and 210, outer right 70 armature and front contact of relay 209, armatures and front contacts of relays 203 and 202 to ground over conductor 208. Relay 344 attracts its armatures and completes a locking circuit for itself over conductor 75 301 to ground.

As soon as sequence switch 114 leaves position 16½, relay 202 releases, permitting relay 209 to retract its armatures and relay 218 to lock in series with relay 217 to 80 grounded conductor 208 through the innermost right armature and front contact of relay 217. This completes the selection of the tens lamp controlling relays, relays 341 and 344 having been actuated.

85 It will now be noted that the units sequence switch register 113 has been set in position 8. When sequence switch 114 is rotated through positions 17+17½, a positive pulse is sent out over a path from grounded battery, resistance 142, upper contact of cam 133, lower contact of positive cam 156 of units register 113, upper contact of cam 139 and over the impulse circuit to ground at the lower contact of cam 140. Relay 201 90 operates in response to this impulse and closes a circuit for units lamp controlling relay 351 which may be traced from grounded battery, left winding of relay 351, conductor 309, middle right armatures and front contacts of relays 217 and 214, left armatures and front contacts of relays 211 and 206, left armature and back contact of relay 207, armature and front contact of relay 201 to 95 ground over conductor 208. Relay 351 operates in this circuit and locks to conductor 301 through both windings in series and its innermost armature and front contact.

100 In position 18+18½, a heavy negative impulse is transmitted from grounded battery, low resistance 144, upper contact of cam 149, lower contact of negative cam 155 of units register 113 over the circuit previously described to ground through the upper 105 contact of cam 140. In response to this impulse, relays 202 and 203 attract their armatures. Through the front contact of relay 202, the circuit is closed for relay 207. Upon the actuation of relay 207, a circuit is closed 110 for relay 219, from grounded battery, winding of this relay, inner left armature and back contact of relay 221, the inner left armatures and front contacts of relays 218, 215, 213 and 210, the outer right armature and front contact of relay 207 to ground 115 over conductor 208.

120 In response to this impulse, relay 352 is also operated over a circuit traceable from grounded battery, left winding of this relay, conductor 308, inner right armatures and 130

front contacts of relays 218, 215, 213 and 210, outer right armature and back contact of relay 209, armatures and front contacts of relays 202 and 203 to ground over conductor 208, whereupon relay 352 locks to grounded conductor 301.

While sequence switch 114 is rotated through positions 19+19½, no positive pulse is sent out but relay 202 is permitted to deenergize again energizing relay 209 in the series circuit with relay 207 as previously described.

In positions 20+20½, of sequence switch 114, a heavy negative impulse is transmitted from grounded battery, lower contact of cam 149, upper contact of negative cam 155 of units register 113 over the impulse circuit to ground at the upper contact of cam 140. Relays 202 and 203 attract their armatures in response to this impulse and relay 202 completes a circuit through the right winding of relay 209 and short-circuits relay 207.

In response to this impulse, relay 354 is also operated over a circuit traceable from grounded battery, left winding of relay 354, conductor 311, outer left armatures and front contacts of relay 218, 215, 213 and 210, outer right armature and front contact of relay 209, armatures and front contacts of relays 203 and 202, to ground over conductor 208 whereupon relay 354 locks to ground over conductor 301.

As soon as sequence switch 114 leaves position 20½ relay 202 becomes deenergized. In response to the retraction of the armature of relay 202, relay 209 becomes deenergized and at its inner right armature and front contact opens the short-circuit about relay 221 which thereupon becomes energized in series with relay 219 through the inner right armature and front contact thereof.

When relay 217 operated, it closed a circuit from ground through its left armature and front contact, conductor 222, winding of relay 310 to grounded battery. This last mentioned relay attracts its armatures to supply battery for lighting the thousands and hundreds digit lamps. When relay 221

attracted its armatures, at its outer left armature and front contact, it connected ground to conductor 223 over which the circuits of certain of the stations lamps may be completed. At the outer right armature and front contact of relay 221, a circuit is closed for lighting the selected units indicating lamps; at the outermost right armature and front contact of relay 219, a circuit is closed for lighting the tens indicating lamps and at the outer left armature and front contact of relay 219, a circuit is closed for lighting the selected stations indicating lamps.

It will be remembered that the thousands digit is 4 and that relay 323 has been actuated and locked. When relay 310 attracts

its armatures, a circuit is closed from grounded battery, outer right armature and front contact of relay 310, outer left armature and back contact of relay 324, outer left armature and back contact of relay 322, outermost right armature and back contact of relay 321, inner left armature and front contact of relay 323, through lamp 4, outer left armature and front contact of relay 323, inner right armature and front contact of relay 310, to ground over conductor 208. The circuits for lighting the hundreds, tens and units digits lamps may be similarly traced.

The stations lamp W will be illuminated over a circuit extended from grounded battery, outer left armature and front contact of relay 219, conductor 224, through lamp W, outer left armature and front contact of relay 262, right armature and front contact of relay 264, to ground over conductor 208.

It will be understood that as soon as the impulse transmitting device 114 has completed its operation, it will come to rest and the cord finder whose brushes are designated by the characters 105 and 106 as well as the associated sequence switch are restored to normal. At the same time, a sequence switch, only certain of the contacts of which are shown, associated with the trunk selecting switch is moved out of position 11 to open the upper contacts of cams 135 and 119 and to close the lower contacts of these cams. The B operator upon noting the number of the wanted line inserts the plug 161 into the jack 162 of this line and depresses the proper ringing key 163 for applying suitable current to the called line to ring the station W which appears on this line. The B operator releases key 127 and effects the deenergization of relays 120 and 200. When relay 200 retracts its armatures, the operated relays controlling the number indicating device appearing in Figs. 2 and 3 are deenergized, due to the removal of ground from conductors 208 and 301 and the number indicating device is placed in condition to indicate a second wanted line.

The further operation of the system in the completion of the call and the restoration of the apparatus on the termination of the call is as described in the above mentioned Patent No. 1,438,743 to E. H. Clark.

The foregoing description clearly illustrates the application and utility of the present invention in a system of the character disclosed and emphasizes the fact that separate generating devices are employed for the positive and negative impulses.

What is claimed is:

1. In a code impulse transmitting system, a line circuit, means to transmit a recurring series of impulses of the same character thereover, and means to modify said series

- of impulses by additional impulses of various characteristics, there being a separate generating device for each character of modifying impulse. 50
5. 2. In a code impulse transmitting system, a line circuit, means to transmit a recurring series of impulses of the same character thereover, and means to modify said series of impulses by additional impulses of various characteristics, there being a separate generating device for each character of modifying impulse, each device comprising a switching device and a register individual to each such generating device. 55
- 10 15. 3. In a code impulse transmitting system, a line circuit, means to transmit a recurring series of impulses of the same character thereover, and means to modify said series of pulses by additional pulses of opposite polarity or increased potential, there being a separate generating device for each said character of modifying impulse, each device comprising a switching device and a register individual to each such generating device. 60
- 20 25. 4. In a code impulse transmitting system, a line circuit, means for transmitting impulses of various characteristics over said line circuit comprising a plurality of registers, a source of current and a switching device, there being a separate section of each register and of said switching device for associating said source with said line circuit for each character of code impulse to be transmitted. 65
- 30 35. 5. In a code impulse transmitting system, a line circuit, means for transmitting impulses of various characteristics over said line circuit comprising a source of current, a plurality of sequence switch registers and a switching device, there being separate cams on each register and on said switching device for associating said source with said line circuit for each character of code impulse to be transmitted. 70
- 40 45. 6. In a code impulse transmitting system, a source of current, a line circuit, means to transmit a recurring series of impulses thereover from said current source and means to modify said series of impulses by additional impulses from said source of various characteristics comprising a switching device and a plurality of registers, each character of modifying impulse being generated by the connection of said source through an individual section of said switching device and of each of said registers. 75
- 50 55. 7. In a code impulse transmitting system, a source of current, a line circuit, means to transmit a recurring series of impulses thereover from said current source and means to modify said series of impulses by additional impulses from said source of various characteristics comprising a sequence switch type switching device and a plurality of sequence switch registers, each character of modifying impulse being generated by the connection of said source through individual cams on said switching device and on each of said registers. 80
- 60 65. 8. In a code impulse transmitting system, a current source, a line circuit, means to transmit a recurring series of impulses thereover from said current source and means to modify said series of impulses by additional impulses from said source of opposite polarity or increased potential comprising a switching device and a plurality of registers, each character of modifying impulse being generated by the connection of said source through individual sections of said switching device and of each of said registers. 85
- 70 75. 9. In a code impulse transmitting system, a source of current, a line circuit, means to transmit a recurring series of impulses thereover from said current source and means to modify said series of impulses by additional impulses from said source of opposite polarity or increased potential comprising a sequence switch type switching device and a plurality of sequence switch registers, each character of modifying impulse being generated by the connection of said source through individual cams on said switching device and on each of said registers. 90
- 80 85. In witness whereof, I hereunto subscribe my name this 16th day of July A. D., 1923. 95

JOHN W. GOODERHAM.
